UNITED STATES PATENT OFFICE.

VICTOR G. FULLER, OF TOULON, ILLINOIS.

DEVICE FOR REGISTERING ELECTRIC CURRENTS.

SPECIFICATION forming part of Letters Patent No. 655,703, dated August 14, 1900.

Application filed December 16, 1899. Serial No. 740,541. (No model.)

To all whom it may concern:

Be it known that I, VICTOR G. FULLER, a citizen of the United States of America, residing at Toulon, in the county of Stark 5 and State of Illinois, have invented certain new and useful Improvements in Devices for Registering Electric Currents, of which the following is a specification, reference being had therein to the accompanying drawings.

This invention relates to registers for electric currents, and particularly to that class designed for recording the length of time during which an electric circuit is closed.

The objects of the invention are, first, to provide a novel combination whereby the closing of a circuit by means of an ordinary knife pattern-switch, either double or single pole, a spring of a timing mechanism is wound; second, to supply a lever under control of an electric magnet whereby the closing of the switch-circuit releases the timing mechanism, thus starting the clock-movement, and whereby the opening of the circuit arrests the movement of the clock and holds it till the closing of the circuit again; third, novel means whereby the number of hours the circuit is closed and the clock runs is recorded by means of hands and dials; fourth, to provide novel means for the automatic opening of the circuit a short time before the clock-spring is unwound by means of a mechanical cut-out independent of the switch; fifth, to provide novel means for closing the cut-out by the movement of the switch-arm in opening and closing the circuit at the switch, and, sixth, to provide a novel combination of the timing mechanism, indicators, electric switches, electric cut-outs, winding and starting mechanism, suitably integrated and under the control of an external switch-arm and winding-lever.

Finally, the object of the invention is to provide a device of the character noted which will prove comparatively inexpensive, durable, and efficient.

With the above and other objects in view the invention consists in the details of construction and in the arrangement and combination of parts to be hereinafter more fully set forth and specifically claimed.

In describing the invention in detail refer-

ence will be had to the accompanying drawings, forming a part of this specification, wherein like characters denote corresponding parts in the several views, and in which— 55

Figure 1 is a face view of the meter-casing. Fig. 2 is a view of the mechanism with the casing removed. Fig. 3 is a sectional view with the automatic cut-out removed. Fig. 4 is a view in elevation, partly in section, of the combined winding-lever and switch-arm and its connections. Fig. 5 is a rear view of the combined winding-lever and switch-arm, and Fig. 6 is a detail view of the winding-wheel. 65

In the drawings, 1 denotes a casing, which may be of any desired configuration, and 2 is one of the two sections forming a frame having bearings for the spindles, &c., the other section being a duplicate of the one shown. 70

The escapement 3, the balance-wheel 4, the escape-lever 5, the spring-controlled main wheel 6, the minute-wheel 7, and the wheels 8 and 9, taking motion from the minute-wheel, being in construction the same as an ordinary clock-movement may not be described in detail. Mounted on the spindle with the minute-wheel are two pinions, the one back of the minute-wheel meshing with the wheel 8 and the one in front of the minute-wheel 80 meshing with one of a train of gear-wheels 10. The spindles of the gear-wheels carry hands 12, which move over the dials 13 on the outer face of the casing. The teeth of the gear-wheels and pinions of this train are so proportioned as to allow ten rotations of one spindle to one rotation of the spindle next thereto, starting from the source of power. 85

The winding-shaft a is extended through the casing and has mounted thereon a pinion a' , meshing with and taking motion from an internal gear-wheel a^2 . The periphery of the wheel a^2 is provided with a shoulder a^3 , engaged by a spring-pressed dog a^4 . The dog is slidable in suitable guides on the combined winding-lever and switch-arm a^5 , through which means the gear-wheel a^2 is rotated. A cam-trip a^6 is secured to the face of the casing, and when the combined winding-lever and switch-arm has made electrical connection with the switch a^7 the trip will have thrown the dog out of engagement with the 90 95 100

shoulder of the wheel, and as the movement of the lever and the rotation of the wheel have served to wind the spring of the main wheel the indicating or timing mechanism starts 5 and continues to run until the tripping device (to be hereinafter described) performs its functions.

The switch a^7 has a connecting-wire b^1 leading to the line and a wire b^2 connected to the 10 cut-out switch b^3 within the casing, the cut-out arm b^4 acting in conjunction with the cut-out switch. A wire b^5 connects the cut-out arm and the magnet b^6 , and a wire b^7 leads from the magnet to the load, thus completing 15 the circuit through the meter.

The winding-shaft is provided with a toothed wheel c , meshing with a larger toothed wheel c' . When the spring is wound, the wheel c' will move in the direction of the arrow, and the insulated stud c^2 thereon will engage the cut-out arm b^4 and press it into contact with the cut-out switch, at the same time the switch a^7 is closed and a circuit is completed from the wire b^2 to the wire b^7 25 through the cut-out switch and the magnet. As the magnet is energized it attracts an armature d , which is on a lever d' , said lever having its end in engagement with a pin d^2 of the balance-wheel when the circuit is open. 30 As the magnet attracts the armature the end of the lever releases the balance-wheel and the timing mechanism starts.

A spring-pressed latch-lever e is pivoted to a frame and has a shoulder engaging the 35 cut-out arm when the circuit is closed, it being understood that the parts are suitably insulated, so that the current may pass only through the cut-out arm and the connections heretofore described.

40 When the timing mechanism is in operation the wheel c' will rotate in a direction opposite to that indicated by the arrow and the insulated pin will pass around and abut the lever e . At the time the pin engages the lever the spring is unwound and the timing mechanism will cease to operate. If the current continued there would be no provision for keeping record. Hence it is desirable 45 that the circuit be opened, and that result is automatically attained by the pin throwing the latch e out of engagement with the end of the cut-out lever, said lever being forced from the cut-out switch by a spring f . In case the electric connection is broken or in 50 the event of such diminution of the current as to reduce the strength of the magnet the armature would be released, its lever would engage the pin of the balance-wheel, and the timing mechanism would be stopped during 55 the interruption of the current.

Having fully described the invention, what I claim as new, and desire to secure by Letters Patent, is—

1. In combination with the timing mechanism, a combined winding-lever and switch-arm, a dog thereon whereby it is connected with the winding mechanism and a cam-trip

for disengaging the dog from the winding mechanism as the circuit is closed.

2. In combination with the timing mechanism, a cut-out switch, a cut-out arm suitably pivoted, means for winding the timing mechanism, a wheel carrying a stud rotated by the timing mechanism, said stud being so arranged as to operate the cut-out lever; a latch 75 for holding the cut-out lever in contact with the switch, said latch being in the path of travel of the stud whereby it is tripped and the cut-out switch released.

3. In combination with a timing mechanism of the character noted, a combined lever and switch-arm, an internal gear-wheel having a peripheral shoulder, a pinion of the winding device meshing with the internal gear-wheel, a dog on the winding-lever and 85 switch-arm, a switch, a cam-trip for disengaging the dog from the peripheral shoulder, a cut-out switch, means whereby the cut-out switch is closed by winding the spring of the timing mechanism, means whereby the cut-out switch is held closed, a magnet in circuit with the switch and cut-out switch, and means controlled by the magnet for arresting the balance-wheel of the timing mechanism. 90

4. In combination with a timing mechanism of the character described, a switch, a combined winding-lever and switch-arm, a cut-out switch, a cut-out switch-lever and a magnet in electrical connection, a latch for holding the cut-out switch and its arm in contact, and a wheel under control of the timing mechanism for tripping the latch and releasing the cut-out lever. 100

5. In combination with a timing mechanism of the character described, a cut-out 105 switch and its lever, means for throwing the lever and switch in contact when the spring of the winding mechanism is wound, a latch for retaining the parts in contact, a wheel carrying a pin for engaging and throwing the 110 latch out of engagement with the cut-out lever, a magnet in circuit with the cut-out arm, an armature for controlling a lever, said lever being arranged to arrest the timing mechanism when the magnet releases the armature. 115

6. In a register for electric currents, a casing having a switch, a combined winding-lever and switch-arm acting in conjunction with the switch, a gear-wheel operated by the 120 winding-lever, connections from the gear-wheel to the spring of the winding mechanism, a cut-out switch and lever within the casing, a wheel rotated by the action of the timing mechanism, an insulated pin on the 125 wheel for throwing the cut-out lever into contact with the cut-out switch when the spring is wound, means for holding the cut-out lever and cut-out switch in contact until tripped by the pin of the wheel and means whereby 130 the timing mechanism is arrested when the cut-out switch is opened or when the strength of the current diminishes.

7. In a register for electric currents, the

timing mechanism, a cut-out, a controlling-wheel rotated by the timing mechanism, a latch for holding the cut-out switch closed, means for tripping the latch, a magnet in circuit with the cut-out switch, a lever controlled by the magnet for arresting and releasing the timing mechanism, a switch, a winding-lever and switch-arm, means thereon for engaging and rotating a gear-wheel

and a trip for releasing the gear-wheel when 10 the circuit is closed.

In testimony whereof I affix my signature in the presence of two witnesses.

VICTOR G. FULLER.
